UNITED STATES PATENT OFFICE.

THEODORE HERKERT, OF CHICAGO, ILLINOIS.

HOLDING DEVICE.

Application filed December 8, 1920. Serial No. 428,106.

To all whom it may concern:

Be it known that I, THEODORE HERKERT, a citizen of the United States, residing at Chicago, in the county of Cook and State of Illinois, have invented new and useful Improvements in Holding Devices, of which the following is a full, clear, concise, and exact description, reference being had to the accompanying drawing, forming a part of this specification.

My invention relates to holding devices and it has special reference to holders for such articles as pressing irons or flat irons and particularly electric pressing irons.

My present holder is adapted to be secured to a flat surface, such as a partition of a trunk or a trunk tray or the like and, therefore, is of considerable service and convenience in transporting travelers' irons. The holder of my present invention is adapted to receive all forms of standard pressing irons. It serves to hold an iron in fixed position so as to preclude the iron, during transit in the trunk, from moving about thereby disarranging or damaging other articles that may be likewise placed in the same trunk compartment. When my holder is devoid of the iron, the holder may be folded up into a compact structure occupying very little space.

An object, therefore, of my present invention is to provide a holder of the above indicated character for a pressing iron or other similar article which will be economical to construct, easy to position on a suitable support, such as a trunk tray or a trunk bottom, and effective in holding a pressing iron of any standard form. At the same time, the holder of my invention when not in use may be folded up compactly thereby permitting such space to be utilized for other purposes.

Other objects of my invention will appear more fully from reference to the following description and the accompanying drawing, in which:

Fig. 1 is a view in elevation of a holding device embodying a form of my invention and in which an electric pressing iron of standard form is shown in outline.

Fig. 2 is a view similar to that of Fig. 1 in which my holding device is shown in such position that the pressing iron may be readily withdrawn therefrom, and

Fig. 3 is a plan view of the holding device

of Figs. 1 and 2 showing the yoke member in its folded-up position.

Referring to the drawing, a base member or base plate 1 of my holder is formed of a resilient strip in the form of a standard angle iron, one of the sides of the angle iron being cut at spaced intervals and portions thereof removed to form a series of spaced securing lugs 2. The angle iron is so shaped as to conform generally to the shape of the smoothing plate of a pressing iron. At the corner 3 and the nose 4 of the angle iron, the material forming the lower side of the angle iron is removed so that the proper curvature to the base plate 1 may be imparted at these portions. The base portion 5 of the base plate 1 is spaced from the side portion 6, as shown at 7 in order that the base plate may be adjusted to fit the smoothing plate of any size of standard pressing iron. Because of the resiliency of the member forming the base plate 1, this adjusting may be readily and conveniently effected. Each of the lugs 2 is provided with an opening through which a holding screw 8 may project for securing the holder to any suitable surface, such as 9. The surface 9 may constitute a partition of a trunk compartment or a tray wherein it may be convenient to place the holder in order that it may receive a traveler's pressing iron.

An elongated U-shaped yoke member 10 bridges the two sides of the base plate 1 and is hinged at 11 to the upstanding side of the angle iron constituting the said base plate. The member 10 is elongated to more than bridge the handle 12 of any pressing iron that may be received in the holder, as shown in Fig. 1. The central portion 13 of the U-shaped member 10 is reinforced by means of a plate 14, these plates 13 and 14 being threaded to receive an adjusting bolt 15 that is provided at its outer end with a thumb engaging piece 16. The inner end of the bolt 15 is provided with a semicircular member 17 to which it is secured but permitted to freely rotate therein. The inner face of the member 17 is provided with a leather or felt pad, such as 18, which is interposed between the handle of the retained pressing iron and the engaging member 17 when the elements occupy the position shown in Fig. 1. The iron 12^a is fitted within the base member 1 of the holder and the face of the smoothing plate of the iron rests upon the 110

lugs 2. The yoke member 10 is then moved to its vertical position as shown in Fig. 1 and the adjusting bolt 15 is screwed downwardly in order to firmly hold the iron 12 within the holder. When it is desired to remove the iron from the holder the adjusting bolt 15 is released and the yoke member 10 is rotated downwardly, as shown in Fig. 2. The iron may thus be readily removed from the holder.

When the holder is devoid of an iron, the yoke 10 is positioned as shown in Fig. 3 and the semicircular member 17 is moved through the agency of the adjusting bolt 15 into contact with the nose portion 4 of the base plate 1. By tightening the bolt 15, the yoke 10 is thus held in its lowest position. In this position the holder of my invention occupies substantially negligible space and, at the same time, all of the elements thereof are firmly secured against movement.

While I have shown and described but one embodiment of my invention, it is to be understood that I do not desire to be limited to the specific structure shown in the drawing inasmuch as other modifications may be made in my holder without departing from the spirit or scope of the appended claims.

Having thus described my invention, what I claim as new and desire to secure by Letters Patent is:

1. A holding device for a pressing iron comprising a base member adapted to receive the smoothing plate of a standard pressing iron, a yoke member pivotally hinged thereto, a holding member supported by said yoke member, and a bolt for adjusting said holding member relative to said base member and yoke member or for engaging said holding member with said base member.

2. A holding device for a pressing iron comprising a base member, fastening lugs formed thereupon, a U-shaped yoke member pivotally hinged to said base member and adapted to straddle a pressing iron positioned on said base member, and means secured to said yoke member either for holding said pressing iron in fixed position upon said base member or for holding said yoke member in a plane coincident with the plane of said base member.

3. A holding device for a pressing iron comprising a base member formed of a resilient metal strip bent to conform to the smoothing plate of a pressing iron, fastening lugs secured to said strip and upon which the smoothing plate of said iron may rest, a U-shaped yoke portion straddling said base member and pivotally hinged thereto, and means whereby said yoke portion may either retain the engaged pressing iron in contact with said base member or hold said yoke portion in engagement with an end portion of said base member.

4. A holding device for a pressing iron comprising a base member formed of a resilient metal strip bent to conform to the smoothing plate of a pressing iron of standard form, one leg portion thereof constituting one end of the strip being spaced from one end of the base portion thereof constituting the other end of said strip, a U-shaped yoke member hinged to said base member, and adjusting means for holding said yoke member either in contact with a handle of a pressing iron that may be in position on said base member or with the nose portion of said base member.

5. A holding device for a pressing iron comprising a base member formed of a resilient strip adapted to receive any size of smoothing plate of a standard pressing iron, a holding member hinged to said base member, and adjustable means secured to said holding member for engagement either with a holding member hinged to said base member or with the nose portion of said base member.

6. A trunk flat iron holder comprising a base member, a holding frame pivotally hinged to said base member, means for either securing a flat iron between said holding frame and said base member or for securing said holding frame to said base member when the former occupies a folded-up position, and means for securing said base member to a trunk part.

In witness whereof, I have hereunto subscribed my name.

THEODORE HERKERT.

Witnesses:

GEO. W. HANSEN,
A. ARNOLD BRAND.

Certificate of Correction.

It is hereby certified that in Letters Patent No. 1,434,614, granted November 7, 1922, upon the application of Theodore Herkert, of Chicago, Illinois, for an improvement in "Holding Devices," an error appears in the printed specification requiring correction as follows: Page 2, line 87, claim 5, strike out the words "holding member hinged to" and insert the words *pressing iron positioned on*; and that the said Letters Patent should be read with this correction therein that the same may conform to the record of the case in the Patent Office.

Signed and sealed this 26th day of December, A. D., 1922.

[SEAL.]

KARL FENNING,

Acting Commissioner of Patents.
